ATTORNEY.

UNITED STATES PATENT OFFICE.

LEWIS BENNETT, OF EAST SCHUYLER, NEW YORK.

DESIGN FOR A BASKET.

SPECIFICATION forming part of Design No. 25,927, dated August 11, 1896.

Application filed January 16, 1896. Serial No. 575,785. Term of patent 14 years.

To all whom it may concern:

Be it known that I, LEWIS BENNETT, a citizen of the United States, residing at East Schuyler, in the county of Herkimer and State of New York, have invented and produced a new and original Design for Baskets, of which the following is a specification, reference being had to the accompanying drawings, showing the same.

10 Figure 1 shows a perspective view of a basket, showing my design in upright position. Fig. 2 is a perspective view of my basket in inverted position.

Baskets of my design are of the form shown, 15 constructed of metal and without openings or perforations as distinguished from baskets heretofore made of splints or flexible strips interwoven, and the basket is provided with a small roll A on its upper edge and an inverted bottom B, with handles C C, all sub-

stantially as shown in the drawings. The body of the basket is round and of a slight conical shape between the roll and a point where the material is curved inward to form the bottom.

25

What I claim is—

1. The design of a basket herein shown and described.
2. A basket of the form shown and having rolled edge, an indented bottom, and handles 30 projecting above the edge, as shown and described.

In witness whereof I have hereunto affixed my signature, in presence of two witnesses, at the city of Utica, New York, this 9th day of 35 January, 1896.

LEWIS BENNETT.
